GATE LATCH

Troy J. Knight, Golden, Ill.

Application February 4, 1949, Serial No. 74,543

2 Claims. (Cl. 292—204)

1

This invention relates to a gate latch, and more particularly to a latch for a gate which may be swung about a hinge post for abutting engagement with the side of a latch post.

It is an object of this invention to provide a gate latch of the kind to be more particularly described hereinafter for securing a gate in the closed position in abutment with the latch post. The gate latch is particularly adapted for use with gates which may be supported on the hinge post for swinging movement for abutment with either side of the latch post.

Another object of this invention is to provide a gate latch of this kind which is mounted on the latch post for vertical sliding movement, being frictionally engaged with the mounting means for frictionally securing the latch in a selected vertical position.

Still another object of this invention is to provide a gate latch of this kind having arms swingably mounted on a horizontal pin or bar for vertical swinging movement, and so mounted on the bar that the locking arms may be swung about the rod for engagement thereon in a position opposite from an original position. The locking members are mounted on the bar for swinging movement in a 90° arc, from a locking to an open position, and the arc or path of movement of each of the locking members may be moved 180° from the original path of movement.

With the above and other objects in view, my invention consists in the arrangement, combination and details of construction disclosed in the drawings and specification, and then more particularly pointed out in the appended claims.

In the drawings:

Figure 1 is a side elevation of a gate, having a gate latch constructed according to an embodiment of my invention.

Figure 2 is a front elevation of the gate latch removed from the latch post.

Figure 3 is a horizontal section, partly broken away, taken on the line 3—3 of Figure 1.

Figure 4 is a vertical section taken on the line 4—4 of Figure 2.

Figure 5 is a side elevation of the gate latch, with both of the locking members in the locking position.

Figure 6 is a vertical section taken on the line 6—6 of Figure 3.

Figure 7 is a side elevation, partly broken away, of the tubular member removed from the assembly.

Referring to the drawings, the numeral 10 designates generally a gate which is hingedly supported at one end on a fixed gate post 11. The gate 10 is hingedly mounted on the post 11 by an upper and lower hinge 12, and the outer or free end of the gate 10 is adapted to abut one side of a latch post 14. A latch 15, constructed

according to an embodiment of my invention, is fixed on the post 14 for securing the gate 10 in the locked position.

The latch 15 is formed with an elongated bracket 16 having a vertically extending arm or bar 17 which is adapted to be secured on the post 14 spaced inwardly therefrom. An outwardly extending arm 18 is fixed to or formed on the opposite ends of the bar 17, and an outturned flange 19 extends outwardly from the outer end of the arms 18. The flanges 19 are formed with a central opening 20 therein through which a bolt or other suitable fastening device may be engaged for securing the bracket 16 to the upper end of the latch post 14. A plate 21 overlies the outer surface of the rod or arm 17, and a second plate 22 engages the inner side of the arm 17 opposite from the plate 21. Bolts 24 extend from the plate 21 and threadedly engage the plate 22, said bolts extending through the plates 21 and 22 outwardly from the side edges of the bar 17. A nut 25 is threadably engaged on the inner end of the bolts 24 for clamping the plates 21 and 22 together in frictional engagement with the bar 17.

A tubular bar or rod 26 is fixed to the outer plate 21 and extends horizontally outwardly from the opposite sides thereof. The bar 26 may be secured to the outer plate 21 by welding or other suitable fastening means. Since the plates 21, 22 may be brought into and out of clamping engagement with the opposed side faces of the bar 17 of the bracket 16 by means of the bolts 25, the tubular rod 26 may be selectively adjusted in various positions longitudinally of the post 14 within the limits prescribed by the length of the bar 17 of the bracket 16. In each position the rod 26 is clamped into a fixed position by means of the cooperating plates 21, 22.

A tubular member 27 is rotatably mounted on the outer end of the rod 26, on opposite sides of the bracket 16. The outer end of the tubular member 27 is formed with diametrically disposed cutout portions 28 each having opposed bounding walls and within which a pin 29, fixed on the outer ends of the rod 26 may be engaged with the bounding walls of each cutout for limiting the rocking movement of the tubular member 27. The side edges of the cutout portions 28 are adapted to engage the fixed pin 29 for limiting the rocking movement of the tubular member 27 to 90°.

The tubular member 27 is slidably mounted on the rod 26, and pressed outwardly for engagement with the pin 29 by a spring 30. The spring 30 is coiled about the rod 26, and one end of the spring 30, the end 31, is adapted to be engaged in a groove or opening through the side wall of the tubular rod for securing the spring against sliding movement. The outer end of the spring 30 is adapted to be engaged on the inner surface

of a washer 32 which abuts the inner end of the tubular member 27.

The tubular member 27 when engaged on the rod 26, is normally disposed outwardly from the side edges of the latch post 14, being spring pressed into engagement with the stop pin 29, carried by the outer end of the rod 26.

A U-shaped locking arm 34 is fixed on the outer end of the tubular member 27 extending radially therefrom. The radially extending side arms 35 of the U-shaped member 34 are fixed to the tubular member 27 at their inner ends, and the bight portion 36 is fixed to the outer ends of the arms 35. In the normal position of the locking member 34, the innermost of the side arms 35 will be disposed outwardly from the side wall of the latch post 14, so that when the gate 10 is in the locked position, the inner side of the gate will abut the outer wall of the latch post 14 and the inner arm 35 of the locking member 36 will engage the outer side of the gate for clamping the gate between the outer side of the gate post 14 and the innermost arm 35.

A handle 37 is fixed to the tubular or cylindrical member 27, on the opposite side thereof from the locking arm 34. The handle 37 is formed of an elongated rod extending radially outwardly from the tubular member 27 and may be disposed inwardly from the locking member 34. In the open position of the latch 15, the locking member 34 and handle 37 will be disposed in a substantially horizontal plane, and in the locking position of the latch 15 the locking bar 34 will depend from the lower side of the tubular member 27 and the handle 37 will extend vertically upwardly therefrom.

In the use and operation of the gate latch 15, described above, the gate 10 is initially moved to a closed position whereupon the extreme outer end of the gate will abut one side of the latch post 14. The latch 15 will be slidably adjusted along the bracket 16 so that the rod 26 and tubular members 27 will be disposed immediately above the upper edge of the horizontal bar of the gate. When the locking members 35 are disposed in a downwardly extending relation to the shaft or rod 26, the inner arm 35 of the locking member will engage the outer surface of the gate 10 for limiting the outward swinging movement thereof. The inner surface of the gate 10 will engage the outer surface of the latch post 14 so that the gate is clamped between the locking member 34 and the gate post 14. The same latch 15 may be used on the gate pin when the gate pin is loosened from the hinge connection with the hinge post 11 for swinging movement on the other side of the latch post 14.

I do not mean to confine myself to the exact details of construction herein disclosed, but claim all variations falling within the purview of the appended claims.

What I claim is:

1. A latch for locking a gate to a gate post comprising a vertically disposed bracket adapted to be secured to the inner face of said post adjacent the top thereof, a rod secured transversely of said bracket and adapted to overlie said gate, a tu-

bular member circumscribed about said rod adjacent one end thereof and rotatably and slidably supported on said rod, said tubular member being provided with opposed cutouts on the end contiguous to said one end of said rod, each of said cutouts having opposed bounding walls, stop means arranged transversely of and carried by said rod adjacent said one end thereof and engageable with the opposed bounding walls of each of said cutouts on said tubular member for limiting the rotary movement of the latter, resilient means circumscribed upon said rod inwardly of said tubular member and having one end fixedly secured to said rod and having the other end bearing against the other end of said tubular member for slidably urging said tubular member into engagement with said stop means, and a locking arm dependently supported from said tubular member and movable upon rotary movement of said tubular member into abutting engagement with the face of said gate remote from said post.

2. A latch for locking a gate to a gate post comprising a vertically disposed bracket adapted to be secured to the inner face of said post adjacent the top thereof, a rod secured transversely of said bracket and adapted to overlie said gate, a tubular member circumscribed about said rod adjacent one end thereof and rotatably and slidably supported on said rod, said tubular member being provided with opposed cutouts on the end contiguous to said one end of said rod, each of said cutouts having opposed bounding walls, stop means arranged transversely of and carried by said rod adjacent said one end thereof and engageable with the opposed bounding walls of each of said cutouts on said tubular member for limiting the rotary movement of the latter, resilient means circumscribed about said rod inwardly of said tubular member and having one end fixedly secured to said rod and having the other end bearing against the other end of said tubular member for slidably urging said tubular member into engagement with said stop means, a locking arm dependently supporting from said tubular member and movable upon rotary movement of said tubular member into abutting engagement with the face of said gate remote from said post, and hand actuatable means carried by said tubular member for effecting the rotary movement thereof.
